UNITED STATES PATENT OFFICE

DAVID W. BLAIR, OF NEW YORK, N.Y.

PUMP.

1,196,758.

Specification of Letters Patent.

Patented Sept. 5, 1916.

Application filed September 13, 1910. Serial No. 581,843.

To all whom it may concern:

Be it known that I, DAVID W. BLAIR, a citizen of the United States, and a resident of the city, county, and State of New York, have invented a certain new and useful Improvement in Pumps, of which the following is a specification.

This invention relates to rotary pumps, and especially to the class of pumps intended for pumping acids or acid solutions.

One of the objects of the invention is to provide a pump which will have a very high efficiency and whose parts are so combined that they may be most readily and easily assembled and disassembled.

Other objects will appear from the herein-after description.

In the accompanying drawings: Figure 1 is a vertical section of a pump embodying the present improvements. Fig. 2 is a horizontal section on the line 2-2 of Fig. 1. Fig. 3 is a detail view of the impellers and a portion of their shaft. Fig. 4 is a detail view of the division and cover plates.

The same characters of reference designate the same parts in the several views.

A designates a suitable framework which may be of any suitable shape, size, material and construction. As here shown it embodies a base 11 and a superstructure 12 which latter has a space 13 within which the pump casing B is mounted, and a separate space 14 which receives the pulley 15 by which the pump is driven from any suitable source of power.

The pump casing B is of any suitable construction and as already stated it is mounted in the space 13 and is supported from the base 11.

The impeller shaft 16 is suspended from its bearings 17 and 18 in the frame and extends into the impeller chamber 20 of the pump casing B, to or nearly to the bottom of the latter. Upon it are mounted two impellers C and D, which are spaced apart thereon and are arranged between the suction inlet 21 and the outlet 22 with which the casing is provided.

The casing referred to is preferably formed to provide a tank or vat 23 having the suction inlet 21 and an overflow 24 near its opposite ends, respectively, and its wall below said tank or vat is formed to provide annular channels 25 and 26 which are operatively related to the impellers, as will be more clearly understood from the herein-

after description. The outlet port 22 is connected to the channel 26.

Between the tank or vat 23 and the impeller receiving portion of the casing, the latter is formed to provide a step bearing, having inwardly inclined walls 27 and 28 and an intermediate platform 29. Below this it is formed with a second bearing 30 with similarly inclined walls 31 and 32, and 65 below the latter it has a third bearing 33 with an inwardly inclined wall 34. Its lateral walls are formed to provide openings or ports 35, 36 and 37.

The impellers C and D are mounted on 70 the shaft 16 and are held in their spaced relation thereon by providing one with an outwardly extending and the other with an inwardly extending member as 40 and 41 respectively, having shoulders 42. One of 75 these members receives the other and each of them is seated against the shoulder of the other. The inner impeller C has its hub 43 mounted against a nut 44 on the end of said shaft, whereby it is held against inward 80 movement on the shaft. Each of these impellers comprises an inner wall 45 and an outer wall 46, the latter preferably inclined outward from the shaft and having an opening 47 around its hub for the inlet of liquid 85 to the space 48 between said walls. Curved vanes or wings 49 radiating from the hub, are disposed in said space 48 and serve by their centrifugal action to throw the liquid out from the impeller through the open periphery of the latter and into the adjacent channel in the pump casing.

A hollow division plate E is mounted in the space between the two impellers. This division plate E is composed of inner and 95 outer members 50 and 51 which are mounted on the seats or bearings 30 and 33, respectively and are connected with each other by lugs or webs 52, which are spaced apart to provide openings 53 to register with the 100 ports 36 and thus serve as a means by which the interior of the division plate has communication with the channel 25. The interior of this division plate also has communication with the interior of the impeller 105 C by means of an opening 54 in its lower wall, which registers with the opening 47 in the outer wall of said impeller.

A covering plate F, having a peripheral flange 55 at its outer edge seated upon the 110 platform 29 is mounted in the opening leading to the impeller chamber 20 of the pump

casing, and is provided with an opening 56 which registers with the inlet opening 47 of the upper impeller. This covering plate has inwardly extending lugs 57 which, as 5 most clearly shown in Fig. 4 are seated on the outer member 50 of the division plate. These lugs 57 are arranged to provide openings 58 by which the interior of the impeller D has communication with the channel 25 10 of the pump casing, through the inlet ports 35 in said casing. It will be noted that the body of the cover plate and the inner wall 50 of the division plate are each shown as being concave to conform to the illustrated 15 convex surfaces of the impellers presented thereto, respectively, and that said cover and division plates are fixed with relation to the impellers and are free from contact with the latter.

20 The parts are removably secured in operative relation by means of rods 60 whose lower ends are seated in sockets 61 with which the outer surface of the covering plate is provided, while their upper ends 62 are pointed 25 and seated in holding devices 63 adjustably secured to the web or wall 17 of the frame. These holding devices are shown as screws whose heads are provided with seats 64 for the pointed ends of the rods, the shanks of 30 said screws being mounted in threaded apertures 65 in said wall having a length such as to provide a clearance space 66 when the screws are engaged with the rods, this clearance space adapting the screw to be 35 moved out of engagement with the rod.

It will be noted that when the parts are assembled in the positions described acid or other liquid to be pumped, which may be poured into the tank or vat 23 or find its 40 way thereto through the suction inlet 21, will be drawn by the impeller D and forced out into the channel 25 and thence, by the combined pressure of the impeller D and the suction of the impeller C, will be drawn 45 through the port 36 into division plate E and thence into the impeller C, by which it will be forced out into the channel 26 and finally through the outlet 22. As a result of this combination of parts a pump is produced 50 which is capable of developing very high power. It will also be noted that the parts may be very readily assembled and when assembled are securely held in their proper positions. It should be here stated 55 that the described beveling of the walls adjacent to the seats for the cover plate F and division plate E, and the corresponding beveling of the walls of said plates, which are in contact with the walls first referred 60 to, provides a means whereby said plates may be tightly held in place and wear of the contacting surfaces readily taken up.

In assembling the parts the impeller C is slipped onto the shaft; the division plate D 65 is then forced into its seat, over said im-

pellers; the impeller D is next forced until its hub engages the hub of the impeller C; and after this has been done the cover plate F is forced to its seat and is secured by the holding rod and holding devices 63. In 70 disassembling the parts the holding devices 63 are adjusted into their sockets until the rods 60 are freed and when this has been done the parts can be readily removed for cleaning purposes, renewal or repair or for 75 any other purpose.

In order to enable the parts of the pump which are in contact with acid or with acid solution, to resist the action thereof, when the pump is employed for such material, the 80 impeller shaft 16 and the rods 60 are lined with acid proof material, as indicated at 70 and 71 respectively, or other suitable provision is made for rendering them acid proof. The cover and division plates and 85 the impellers, and their parts which come in contact with the acid also are suitably made proof against the same by forming them of lead or other acid-proof material or by lining them with an acid-proof material. This is also true of course of the 90 pump casing.

Attention is called to the fact that in the 95 illustrated embodiment of the invention the impellers are shown as being free from contact with the cover and division plates and also with the pump casing. They therefore operate without friction. In fact it will be noted that there are no moving parts in contact with stationary parts within the pump. 100 Hence heating due to frictional contact between stationary and moving parts is entirely overcome. This is an advantage particularly when the liquid being pumped is an acid, as will be readily understood.

105 It is believed that the construction, operation and advantages of the invention will be clearly comprehended from the foregoing description and it should be noted that the invention in its broader aspects is not restricted to the details illustrated and may be varied with respect to such details without departing from its spirit or the scope of the subjoined claims.

Having thus described the invention what 110 is believed to be new and desired to be secured by Letters Patent, is:

115 1. In a rotary pump, a casing having spaced passages, one of the passages being provided with spaced inlet and outlet ports, the wall of the casing having a seat between said ports, the other passage having a port, the casing having a seat between the latter port and the outlet port of the first mentioned passage, a division plate mounted on 120 said seats and internally having communication with the first mentioned passage through the outlet port of the same, an impeller chamber above and division plate, an impeller chamber below said division plate,

an impeller mounted in each of said chambers, one of said impellers having communication with the first mentioned passage through the inlet port of the same and the other impeller having communication with the other passage through the port to the same, the last mentioned impeller and the division plate having communication with each other, and the casing having a liquid inlet to the first impeller and a liquid outlet 10 from the second mentioned passage.

2. In a rotary pump, a casing having spaced passages, one of the passages being provided with spaced inlet and outlet ports, the wall of the casing having a seat between said ports, the other passage having a port, a casing having a seat between the latter port and the outlet port of the first mentioned passage, a division plate mounted on 15 said seats and internally having communication with the first mentioned passage through the outlet port of the same, the wall of the casing above the division plate resting on said seat, an impeller chamber 20 between said division plate and said cover plate, an impeller chamber between said division plate and an end of the casing, an impeller mounted in each chamber, one of said impellers having communication with 25 the first mentioned passage through the inlet port to the latter, and the other impeller having communication with the other passage through the port to the same, the last mentioned impeller and the division plate 30 having communication with each other, and the cover plate having an aperture leading 35 to the first mentioned impeller.

3. In a rotary pump, a casing provided with a well in the upper part thereof and 40 having an inlet communicating with said well, said casing provided with spaced passage below the well, a hollow division plate mounted between said passages and having an inlet and an outlet, a cover plate mounted 45 between the well and the division plate and forming with the division plate an impeller chamber, a second impeller chamber being formed between the division plate and the bottom of the casing, the cover plate 50 having an opening between said passages and having an inlet and an outlet, a cover plate mounted between the well and the division plate and forming with the division plate an impeller chamber, a second impeller 55 chamber being formed between the division plate and the bottom of the casing, the cover plate having an opening communicating with one of said impeller chambers, the said chamber having an outlet communicating 60 with one of said passages, the other chamber having an inlet communicating with the hollow division plate and an outlet communicating with the second passage, a shaft, a plurality of impellers mounted on said shaft 65 and in said chambers, one of said impellers

being disposed in operative relation with the opening in the cover plate and communicating with the first mentioned passage, and the other impeller being disposed in operative relation to the outlet opening in the division plate and communicating with the second mentioned passage. 70

4. In a rotary pump, a casing having a well in the upper part thereof and spaced passages in the wall thereof below said well, 75 a cover plate seated on the casing and arranged between the well and the portion of the casing containing said passages, said cover plate having an opening through which the well has communication with the latter portion of the casing, the well having an inlet, one of said passages having an inlet port and an outlet port, the wall of the casing having a seat between said ports, the other of said passages having an inlet port 80 and the wall having a seat adjacent thereto, a hollow division plate mounted on said seats and having an inlet opening in communication with the outlet port of the first-mentioned passage, the division plate also having an outlet opening, an impeller shaft, and impellers mounted on said shaft and arranged on opposite sides of the division plate, one of said impellers being in operative relation with the opening of the cover 85 plate and the inlet port to the first-mentioned passage and the other of said impellers being in operative relation with the outlet opening of the division plate and the inlet port to the second-mentioned passage, 90 the latter passage having means for the egress of liquid therefrom. 95

5. In a rotary pump, a casing having a well in the upper part thereof, said well being provided with means for the ingress of liquid thereto and a plurality of impeller-chambers formed in the casing below said well, the casing being provided with a removable cover plate separate from the shaft support between said well and chambers, 105 said cover plate partially closing the entrance to the chambers, and impeller-shaft, and a plurality of spaced impellers mounted on said shaft and in said chambers; the casing also having means for the egress of liquid from said chambers. 110

6. In a rotary pump, a casing having a well in the upper part thereof, said well being provided with means for the ingress of liquid thereto and a plurality of impeller-chambers formed in the casing below said well, the casing being provided with a cover plate removably seated between said well and chambers, said cover plate partially closing the entrance to the chambers and 120 constructed and arranged for removal wholly separate from the operating shaft, a division plate removably seated on the wall of the casing and arranged between said chambers, an impeller shaft, and a plu- 125 130

- rality of spaced impellers mounted on said shaft and in said chambers; the casing also having means for the egress of liquid from said chambers.
- 5 7. In a rotary pump, a casing provided with spaced seats, a cover plate removably mounted upon one of the seats, a division plate removably mounted on the other of the seats, an impeller arranged between said 10 plates, a second impeller arranged inward of the division plate, an impeller shaft extending through said plates and impellers, and carrying the latter, the cover plate having projections engaging the division 15 plate, and means engaging the cover plate for holding both plates in position.
8. In a rotary pump, a casing provided with spaced seats, a cover plate removably mounted upon one of the seats, a division 20 plate removably mounted on the other of the seats, an impeller arranged between said plates, a second impeller arranged inward of the division plate, an impeller shaft extending through said plates and impellers, 25 and carrying the latter, the cover plate having projections engaging the division plate, and means engaging the cover plate for holding both plates in position, said means comprising rods and adjustable holding devices for the rods.
9. In a rotary pump, a casing having inner and outer passages, the outer passage provided with inlet and outlet ports, the inner passage having communication with the 30 pump outlet, a hollow division plate located within the casing between said passages, the said division plate and the bottom of the casing being separated to form an inner impeller chamber, a removable cover plate independent of the shaft support within the 35 casing and separated from the division plate to form an outer impeller chamber, an impeller in the first mentioned chamber and operatively related to the inner passage to 40 force liquid thereinto, the division plate adapted to conduct liquid from the outlet port of the outer passage to the impeller, a second impeller in the outer chamber arranged to force liquid into the outer passage, 45 and an opening in the cover plate leading to said second mentioned impeller, a shaft upon which the impellers are mounted to operate and a support for said shaft.
10. In a rotary pump, a casing having a passage therein, said passage being provided with an entrance, separately formed plates consisting of a covering plate and a division plate removably mounted in said casing at the opposite sides of the entrance to said passage, an impeller mounted in the space between said plates, holding rods engaging the outer covering plate, and adjustable holding devices for said rods.
11. In a rotary pump, a casing provided with passages, the wall of said casing being provided with an aperture which communicates with one of said passages and beveled and provided with seats on opposite sides of said aperture, a hollow division plate removably mounted on said seats and having an aperture registering with the aperture of said wall, an impeller above said division plate, and an impeller below said division plate adapted to force liquid into said passages respectively, the said division plate having direct communication with one of said impellers.
12. In a rotary pump, a casing provided with inner and outer passages, the wall of said casing being beveled and provided with seats, inner and outer spaced impellers arranged in said casing and disposed in such relation to the passages as to force liquid into the same, respectively, a removable cover plate seated within said casing and having a beveled wall engaging the beveled wall of the latter, said plate having an open periphery communicating with the outer passage, a removable hollow division plate, seated in said chamber and having a beveled wall engaging the beveled wall of the latter, said division plate having an open periphery communicating with the outer passage, the internal space of said division plate also having communication with the inner impeller, holding rods engaging the cover plate and adjustable holding devices for said rods.

In witness whereof I have hereunto set my hand at the city, county, and State of New York, this 31st day of August, 1910.

DAVID W. BLAIR.

In presence of—

FRANK EUERNIA,
JOHN J. RANAGAN.
